UNITED STATES PATENT OFFICE.

CONSTAN E. RANG, OF CHICAGO, ILLINOIS.

MECHANICAL PENCIL.

Application filed April 2, 1923. Serial No. 629,352.

To all whom it may concern:

Be it known that I, CONSTAN E. RANG, a citizen of the United States, and resident of Chicago, in the county of Cook and State of Illinois, have invented new and useful Improvements in Mechanical Pencils, of which the following is a description, reference being had to the accompanying drawing, which is a part of this specification.

This invention relates to certain new and useful improvements in mechanical pencils and has for one of its objects to provide a pencil in which the outer shell or barrel is independent of the lead holding and operating mechanism whereby the parts may be readily renewed or repaired and the lead replaced.

It is another object of this invention to provide a mechanical pencil of the desired balance which is so designed and constructed as to permit its production in any convenient size.

One objectionable feature of the mechanical pencils now on the market is the inability to readily renew the lead and it is, therefore, another object of my invention to provide a pencil of the character described in which the pencil may be refilled either from the interior or the exterior.

It is a further object of this invention to generally simplify and improve the structure of mechanical pencils.

And a still further object of this invention resides in the provision of a mechanical pencil capable of production in a size most convenient for use by draftsmen and having delineated thereon scales in long and metric measure.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereto, and in which: Figure 1 is a side view of a pencil embodying my invention;

Figure 2 is an enlarged fragmentary view thereof, parts being broken away and in longitudinal section and parts being in elevation to more clearly illustrate details of construction;

Figure 3 is a view similar to Figure 2 illustrating the parts of the pencil in the positions they occupy after a lead has been ejected therefrom;

Figure 4 is a transverse sectional view taken through Figure 2 on the plane of the line 4—4;

Figure 5 is a transverse sectional view taken through Figure 2 on the plane of line 5—5;

Figure 6 is a transverse sectional view taken through Figure 2 on the plane of line 6—6;

Figure 7 is a fragmentary view of the lower end of the pencil illustrating a slightly modified construction in which the end guide or nut member is extended beyond the shell or barrel end, and

Figure 8 is an enlarged fragmentary detail view, partly in section and partly in elevation, illustrating the medial portion of the pencil mechanism.

Referring now more particularly to the accompanying drawing, in which like numerals designate like parts throughout the several views, numeral 10 designates the shell or barrel of the pencil which may be either round, hexagon, or other shape in cross section and has one end 11 taperingly reduced to form the conventional pointed end.

The shell 10 may be constructed of aluminum, brass, copper, steel or any other material and receives therein a lead holding device or mechanism which is readily removably secured in position by means of a head member 12 carried by an operating screw shaft 13, to be later described. A collar 14 is formed on the screw shaft 13 slightly spaced from the head member to form a groove 15 in which a lug or retaining finger 16 is engageable, the lead holding device being removed from the shell by rotating head 12 to align a slot 17 in the collar with the retaining finger, when the same may be readily withdrawn.

Shaft 13 is centrally bored, as at 18, to receive the inner end of a guide extension 19 which projects downwardly therefrom and has an end guide or nut member 20 on its outer end. Member 20 is preferably of

a shape adapted to conform with the inner wall of the shell end 11 to restrain the guide from rotation, the guide extension being preferably provided with two, opposed, 5 longitudinally extending slots 21, through which project the clutch fingers 22 of a lead holder 23.

The lead holder is in the form of a tube freely slideable over the extension and having 10 opposed longitudinally extended slots 24 retained in adjustment with the slots of the guide extension by the clutch fingers. The upper end of the lead holder is freely 15 slideably, but non-rotatably secured in the lower end of a guide member 25 having a guide nut 26 at its upper end in which the screw shaft 13 is threaded. The guide member 25 may or may not be in the form 20 of a tube having opposed slots also held in alignment with the slots of the guide extension and the lead holder by lugs or fingers 27 on the lower end thereof and projecting into the slots 24.

To insert a lead 30 in the pencil, screw shaft 13 is rotated by the head 12 to draw 25 the guide nut 26 to its uppermost position adjacent collar 14 and the lead is then inserted through the bore 28 of the end guide or nut member 20 until its inner end abuts 30 an extracting rod or pin 29 carried by the guide member 26 and terminating slightly inwardly of the clutch fingers 22, the clutch fingers 22 frictionally engaging the inner 35 end of the lead to secure the same in position.

As the outer end of the lead 30 is consumed, the head 12 is rotated to screw the 40 shaft 13 out of nut 26, as a result of which guide 25 and the lead holder telescope over the guide extension projecting the lead outwardly of the end member 20. When the screw shaft has been turned sufficiently to bring the lowermost ends of the slots 21 45 against the clutch finger 23, a further screwing of the shaft 13 outwardly of nut 26 will cause the lead holder to be telescoped, with the guide extension, into the 50 guide member 25 causing the ejector pin 29 to extend beyond the clutch fingers into the bore 28 of the end member 20, ejecting 55 the lead remaining. The shaft is then rotated in the opposite direction to move the parts to the positions illustrated in Figure 2 for refilling.

The movement of the guide upwardly 60 over the screw 13 is limited by a lug or finger 31 formed on the upper end of the lead holder and engageable in one slot of the guide extension to abut the upper end 65 32 thereof when the guide 26 is rotated its full upward movement.

As will be readily obvious, all of the parts of my improved pencil may be readily renewed, the leads may be readily renewed and when the lead has been con-

sumed down to a small fragment the same is automatically ejected from the pencil.

My pencil is especially adapted for use in a pencil of a size most commonly used by draftsmen and when so used I provide 70 two scales 33 and 34 on the shell 10, the scale 33 being in long measure and the scale 34 being in metric measure to facilitate the work of a draftsman in making sketches and obtaining dimensions of the parts. 75

It will be apparent from the foregoing description taken in connection with the accompanying drawings that I provide a pencil capable of construction in a convenient size and having the desired balance and one in which the lead may be retracted as well as extended, by reason of the same being frictionally secured in the lead holder. 80

What I claim as my invention is:

1. A pencil, comprising a shell, a screw shaft rotatably mounted in the shell, means preventing accidental longitudinal movement of said shaft, an operating head on the shaft and positioned outwardly of one end of the shell, a guide member telescoped over the screw shaft, a nut on the outer end portion of the guide member in which the screw shaft is threaded, a lead holder slideable in the inner end of the guide member, an end guide member mounted in the end of the shell remote from the operating head, a guide extension carried by the end member and having its inner end slideable in the lead holder and screw shaft, and means carried by the lead holder for securing the inner end of a lead therein, the outer end projectable outwardly of the shell through the end member. 90

2. A pencil, comprising a shell, a screw shaft rotatably mounted in the shell, means preventing accidental longitudinal movement of said shaft, an operating head on the shaft and positioned outwardly of one end of the shell, a guide member telescoped over the screw shaft, a nut on the outer end portion of the guide member in which the screw shaft is threaded, a lead holder slideable in the inner end of the guide member, an end guide member mounted in the end of the shell remote from the operating head, a guide extension carried by the end member and having its inner end slideable in the lead holder and screw shaft, means preventing rotation of the guide member in the shell, and means carried by the lead holder for securing the inner end of a lead therein, the outer end of the lead being projectable outwardly of the shell through the end member. 110

3. A pencil, comprising a shell, a screw shaft rotatably mounted in the shell, means preventing accidental longitudinal movement of said shaft, an operating head on the shaft and positioned outwardly of one end of the shell, a guide member telescoped over the screw shaft, a nut on the outer end 120

portion of the guide member in which the screw shaft is threaded, a lead holder slideable in the inner end of the guide member, an end guide member mounted in the end 5 of the shell remote from the operating head, a guide extension carried by the end member and having its inner end slideable in the lead holder and screw shaft, means preventing rotation of the guide member in the shell 10 and the rotation of the guide member, lead holder, and end member with respect to each other.

4. As an article of manufacture, a pencil, comprising a shell, a lower slotted tubular 15 guide member, a lower guide member carried by the lower end of said guide member mounted in the shell, said nut member being

of a shape adapted to conform with that portion of the shell in which the same is mounted, a slotted lead holder, lead engaging fingers on the lower end of said holder and projecting through the slots in the lower guide, a tubular screw shaft surrounding said lower guide member, an upper guide member telescoped over the screw 25 shaft, a nut member on the upper end of the upper guide member, projections carried by the lower end of the upper guide member and adapted to ride in the slots of the lead holder, and a rod carried by and extending 30 downwardly from said upper guide member.

In testimony wherof I affix my signature.

CONSTAN E. RANG.

Certificate of Correction.

It is hereby certified that in Letters Patent No. 1,579,029, granted March 30, 1926, upon the application of Constan E. Rang, of Chicago, Illinois, for an improvement in "Mechanical Pencils," errors appear in the printed specification requiring correction as follows: Page 2, line 101, claim 1, after the word "end" insert the words *of the lead being*; page 3, line 17, claim 4, for the word "nut" read *lower guide*; and that the said Letters Patent should be read with these corrections therein that the same may conform to the record of the case in the Patent Office.

Signed and sealed this 4th day of May, A. D. 1926.

[SEAL.]

M. J. MOORE,
Acting Commissioner of Patents.
